2 Claims. (Cl. 103—126)

This invention relates to liquid pumps and particularly to pumps of the kind adapted to be used in hydraulic transmission systems of the hydrostatic type as the pump or motor thereof.

Particularly in hydraulic transmission systems for winches, it is desired to have pumps operating at relatively high speeds for delivering large quantities of liquid at relatively high pressures. Heretofore, pumps of the kind having radially extending vanes have been most commonly used in such systems, although other kinds of pumps have also been embodied. A difficulty in such pumps is to provide a satisfactory tightening effect between moving faces without undue wear on such faces.

It is an object of the present invention to provide a pump wherein an excellent tightening effect is obtained at moving faces, allowing minimum clearances to be maintained at such faces while avoiding wear as much as possible.

Another object of the present invention is to provide a pump or motor of the stated kind in which stresses on moving parts are relieved as much as possible, whereby the pump or motor may operate at high pressures without any detrimental effect on the pump or motor.

The pump or motor according to the present invention is of the kind comprising a housing, first and second shafts arranged side by side in said housing and mounted for rotation in opposite directions, a first sheave means keyed to said first shaft and carrying a set of protruding segment members protruding in axial direction from one side of said sheave means, a second sheave means keyed to said second shaft and carrying a set of protruding segment members protruding in axial direction from one side of said second sheave means, said second sheave means being axially spaced from said first sheave means, each set of segment members being received within a respective one of two ring channels arranged within said housing so as to overlap at a portion thereof, at which portion said sets of segment members are meshing so that a segment member of the first sheave means will engage into the space between two successive segment members of the second sheave means, and means for relieving axial pressure created against said sheaves by the pumping effect at the rotation of said shafts.

In order that the invention can be more clearly understood, it will now, by way of example, be described with reference to the accompanying drawings in which:

FIGURE 1 is an axial sectional view of a hydraulic pump or motor means in a first embodiment of the invention.

FIGURE 2 is a sectional view of the pump as taken along the line II—II of FIG. 1.

FIGURE 3 is an axial sectional view of a second embodiment.

Whenever referring in this description to a hydraulic pump, it is to be understood that the arrangement of the invention may as well be used as a hydraulic motor. As is well known, the hydraulic motors used in such hydrostatic systems as are used for instance for cargo winches of a ship are in fact pumps the rotors of which are set into rotation by the circulating driving liquid, while the liquid in a pump is set into motion by the movement of the rotor.

For the sake of simplicity the subject matter of the

2

invention will in the course of the description be designated as a pump.

The pump according to FIGS. 1 and 2 comprises a housing constituted of two parts 10 and 11 secured together by bolts 12. Mounted on roller bearings 13 in this housing is a first shaft 14 terminating at one end in a stub shaft 15 extending to the outside of the housing for coupling the pumps to a prime mover, not shown, for instance a diesel engine on a ship. The opposite end of the shaft 14 carries a gear wheel 16 in mesh with a second gear wheel 17 keyed to a second shaft 18 mounted on roller bearings 19 in the housing. The gear wheels 16 and 17 have the same diameters, wherefore the shafts 14 and 18 will rotate with the same rotational speed but in opposite directions.

The first shaft 14 supports a sheave 20 mounted between two thrust ball bearings 21. The second shaft 18 supports a similar sheave 22 mounted between two thrust ball bearings 23. Both sheaves are axially spaced from each other, whereby two circular chambers 24, 25 are formed therebetween, said chambers overlapping at a portion 26. An inlet 27 and an outlet 28 are arranged at said intermediate portion 26.

The first sheave 20 carries in the embodiment shown two diametrically opposed segment members 29, 30 each extending over 90° of the periphery and being tightly fitted into the lower chamber 24. The second sheave similarly carries two diametrically opposed segment members 31, 32 which also extend over 90° of the periphery, said segment members being fitted with a snug fit into the upper chamber 25. The four segment members 29-32 are arranged so that a segment member on the first sheave will mesh between both segment members of the second sheave at the intermediate portion 26. By the mesh of the gear wheels 16, 17 the segment members will, when they meet, be kept at a small distance from each other so that they are not actually in contact.

On the sides of the sheaves opposing the segment members 29-32 recesses 33 are arranged, said recesses communicating with the side carrying the segment members 29-32 by passages 34. In FIGURE 2 only one such recess 33 is shown, but it will be understood that similar recesses are present at each of the portions of the sheaves where no segment member is arranged on the opposite side of the sheave. In the peripheral direction each recess extend over somewhat more than 90°, as shown in FIG. 2.

The shaft 18 is fully enclosed within the housing by means of a block 35 supporting the left hand bearing 19 and a disc 36 (FIG. 1). The right hand end of shaft 18 is covered by the housing part 11. Tightening at the stub shaft 15 of the first shaft 14 is obtained by means of a block member 37 supporting a packing support 38 with associated packing gland 39. These members are kept in position by bolts 40.

Discharge fluid from the hydraulic system is supplied to the housing part 11 enclosing the gear wheels 16, 17 by an opening 41. Bores 41a are arranged to supply lubricating hydraulic fluid to the different ball and roller bearings.

When now considering the mode of action of the pump, it will be easy to see that a pumping action similar to that of a gear pump will be obtained when the sheaves 20, 22 are rotated. However, this pump will not have the disadvantages inherent in conventional gear pumps, as the bearings will not be subjected to undue stresses, whereas the contacting faces on the gear wheels 16, 17 will be lubricated by low pressure fluid.

An important feature in the pump is the arrangement of the recesses 33 and associated bores 34, whereby axial forces created by the fluid under pressure are substantially relieved. Even when operating at high pressures, there

will be no significant decrease in the delivery of the pump and when operating as a hydraulic motor in a hydraulic system, a high torque may be generated by utilising higher pressures. Particularly by relieving axial forces the pressure in the system will not tend to urge coacting members apart.

In the embodiment of FIG. 3 is indicated in a sectional view corresponding to FIG. 2 how a third sheave 42 may be arranged with segment members 43, 44 an inlet 45 and an outlet 46 being arranged to cooperate therewith. Hereby, a double acting pump or motor is obtained, whereby a suitable interconnection of the inlets 27, 45 and the outlets 28, 46 for instance by series connection on one hand and connection in parallel on the other hand enables a stepped delivery or consumption to be obtained.

It should be noted that the use of only two diametrically opposed segment members is given by example only. It is as well possible to have a number of segment members on each sheave. It is also possible to use sheaves having different diameters provided that the linear length of their segment members are equal. Thus, it will be possible to use a larger central sheave than the outer sheaves.

While I have shown only two embodiments of my invention, it will, of course, be understood that I do not wish to be limited thereto since various modifications may be made to the arrangement disclosed, and I aim by the appended claims to cover any such modifications as fall within the true spirit and scope of the invention.

What I claim is:

1. A hydraulic pump comprising, a housing, first and second shafts arranged side-by-side in said housing and mounted for rotation in opposite directions, a first sheave keyed to said first shaft and carrying a set of protruding segment members extending in axial direction from one side of said sheave, a second sheave keyed to the second shaft and carrying a set of protruding segment members protruding in axial direction from one side of said second sheave, said second sheave being axially spaced from the first sheave, each set of segment members being received within a respective one of two ring channels arranged within said housing so as to overlap at a portion thereof, at which portion said sets of segment members are mesh-

ing so that a segment member of the first sheave will engage into the space between two successive segment members of the second sheave, means for relieving axial pressure created against said sheaves by the pumping effect at the rotation of the shafts, said means for relieving the axial pressure consisting of arcuate recesses arranged along the side face of the sheaves opposite to the face thereof on which the segment members are located, each of said recesses extending over a peripheral distance somewhat greater than the peripheral spacing between successive segment members, the sheaves being provided with bores extending transversely through them at points between the segment members and which bores establish communication, during rotation of the sheaves, between the arcuate recesses and the ring channels.

2. A hydraulic pump according to claim 1, wherein the bores through the two sheaves are arranged so that the bores in both of the sheaves establish communication at times between the respective arcuate recesses and the same portion of the ring channels.
